CLAIM

We claim the ornamental design for a bulb shaped medical instrument handle with wells, as shown and described.

DESCRIPTION

FIGS. 1 and 2 are side elevations offset 180 degrees of a bulb shaped handle with wells showing our new design;
FIGS. 3 and 4 are top and bottom elevations offset 180 degrees of a bulb shaped handle with wells showing our new design;

FIG. 5 is a front view thereof;

FIG. 6 is a rear view thereof;

FIG. 7 is a perspective view front to back thereof; and,

FIG. 8 is a perspective view rear to front.

The broken lines showing the remainder of the medical instrument are directed to environment and are for illustrative purposes only; the broken lines form no part of the claimed design.

1 Claim, 5 Drawing Sheets
